DISPENSING CONTROL CLOSURE FOR A
CONTAINER

Ralph B. Waite, Springville, N. Y.

Application July 22, 1949, Serial No. 4,069

Term of patent 14 years

(Cl. D58—26)

To all whom it may concern:

Be it known that I, Ralph B. Waite, a citizen of the United States, residing at Springville, in the county of Erie and State of New York, have invented a new, original, and ornamental Design for a Dispensing Control Closure for a Container, of which the following is a specification, reference being had to the accompanying drawing, forming part thereof.

Fig. 1 is a side elevational view of a dispensing control closure for a container, showing my new design;

Fig. 2 is a top perspective thereof;

Fig. 3 is a bottom plan view thereof;

Fig. 4 is a top plan view thereof; and

Fig. 5 is another side elevational view thereof.

I claim:

The ornamental design for a dispensing control closure for a container, as shown.

RALPH B. WAITE.
